US00D898003S

(12) **United States Design Patent** (10) Patent No.: **US D898,003 S**
Lee et al. (45) Date of Patent: ** Oct. 6, 2020

(54) **NOTEBOOK COMPUTER**

(71) Applicants: **Shang-Che Lee**, Taipei (TW); **I-Lung Chen**, Taipei (TW); **Wang-Hung Yeh**, Taipei (TW); **Ching-Hua Li**, Taipei (TW); **Hsiao-Ching Hung**, Taipei (TW)

(72) Inventors: **Shang-Che Lee**, Taipei (TW); **I-Lung Chen**, Taipei (TW); **Wang-Hung Yeh**, Taipei (TW); **Ching-Hua Li**, Taipei (TW); **Hsiao-Ching Hung**, Taipei (TW)

(73) Assignee: **COMPAL ELECTRONICS, INC.**,
Taipei (TW)

(**) Term: **15 Years**

(21) Appl. No.: **29/648,952**

(22) Filed: **May 24, 2018**

(51) LOC (12) Cl. **14-03**

(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof with the display opened;

FIG. 9 is a front view thereof with the display opened;

FIG. 10 is a rear view thereof with the display opened;

FIG. 11 is a left side view thereof with the display opened;

FIG. 12 is a right side view thereof with the display opened;

FIG. 13 is a top view thereof with the display opened; and,

FIG. 14 is bottom view thereof with the display opened.

The dashed broken lines illustrate portions of the notebook computer and form no part of the claimed design.

1 Claim, 11 Drawing Sheets
